UNITED STATES PATENT OFFICE.

GEORGE F. KINNEY, OF NEW YORK, N. Y.

REMINDING DEVICE.

1,173,585.

Specification of Letters Patent. Patented Feb. 29, 1916.

Application filed March 6, 1913. Serial No. 752,460.

To all whom it may concern:

Be it known that I, GEORGE F. KINNEY, a citizen of the United States, and resident of the borough of Manhattan, in the city and State of New York, have invented a new and useful Improvement in Reminding Devices, of which the following is a specification.

The object of my invention is to provide certain improvements in the construction, form and arrangement of the several parts of a reminding device whereby the pointers will be held in their adjusted positions against unintentional displacement.

A practical embodiment of my invention is represented in the accompanying drawings, in which—

Figure 1 represents the reminding device in front elevation, and Fig. 2 is a section taken in the planes of the line A—A of Fig. 1.

The reminding device comprises a dished plate, the depressed portion of which is denoted by 1 and the rim portion by 2. The rim portion 2 of the plate is provided with an annular series of reminders 3, which reminders may be of any desired character according to the use to which the reminding device is to be applied. A plurality of pointers 4 are pivoted on a common axis. In the present instance the pointers are pivoted upon a hollow pin 5 uprising from the depressed portion 1 of the plate centrally with respect thereto. The plate is provided with an annular series of holes 6 corresponding to the reminders 3 and the pointers 4 have inwardly turned points 7 adapted to enter the said holes 6 so as to hold the pointers against unintentional displacement when adjusted to the desired reminders. These pointers are spring pressed so as to tend to force their inwardly turned points

into the said holes 6. In the present instance, I have shown the reminding device as a kitchen reminder but it is obvious that it may be used for any desired purpose where a reminding device would be of value.

The reminding device may be provided with a loop 8 for suspending the device from a support, if so desired, or a nail may be driven through the hollow pin 5 for securing the device to the support.

It is evident that slight changes might be resorted to in the form, construction and arrangement of the several parts without departing from the spirit and scope of my invention; hence I do not wish to limit myself strictly to the structure herein set forth, but

What I claim is:—

As an article of manufacture, a plate having a depressed central portion and a flared rim portion, said rim portion having an annular series of names of articles and a corresponding series of holes at the inner edge of the rim portion, a centrally arranged pin uprising from and within the depressed central portion of the plate and a plurality of spring-pressed pointers pivoted and free to be rotated on said pin and having inwardly turned points adapted to enter said holes to hold the pointers in their adjusted positions below the plane of the peripheral line of the plate against unintentional displacement.

In testimony that I claim the foregoing as my invention, I have signed my name in presence of two witnesses, this fifth day of March 1913.

GEORGE F. KINNEY.
